UNITED STATES PATENT OFFICE.

ELMER B. STONE AND CHARLES E. JOHNSON, OF NEW BRITAIN, CONNECTICUT,
ASSIGNORS TO THE AMERICAN HARDWARE CORPORATION, OF NEW BRIT-
AIN, CONNECTICUT, A CORPORATION OF CONNECTICUT.

DOOR AND LOCK THEREFOR.

1,362,647.

Specification of Letters Patent. Patented Dec. 21, 1920.

Application filed May 13, 1916. Serial No. 97,316.

To all whom it may concern:

Be it known that we, ELMER B. STONE and CHARLES E. JOHNSON, each a citizen of the United States, and a resident of New 5 Britain, in the county of Hartford and State of Connecticut, have invented a new and Improved Door and Lock Therefor, of which the following is a specification.

Our invention relates more especially to 10 the class of locks employed for securing doors and similar devices, and an object of our invention, among others, is to provide a removable lock that may be applied to different doors, but that shall be adapted 15 for use particularly in connection with doors or similar devices especially constructed to receive it: and a further object of our invention is to provide a lock having simple means for indicating certain conditions: and 20 a further object of our invention is to so construct a lock that the door and door casting shall be rigidly united, whereby the bolt may not be surreptitiously disengaged from 25 its keeper.

One form of door, frame and lock therefor, embodying our invention is shown in the accompanying drawings, in which—

Figure 1 is a face view of a door frame and door showing the latter locked with our 30 improved lock, the signal being in the position assumed when the lock has been secured by the use of a master key.

Fig. 2 is a similar view showing the position of the signal assumed when the lock 35 has been secured by a common key.

Fig. 3 is a face view of a part of a large door and frame with parts broken away to show construction, and with the signal in the same position as shown in Fig. 2.

40 Fig. 4 is a view showing the lock plate and lock supported by the door frame in position to permit opening movement of the door.

Fig. 5 is a view of the lock plate and lock, 45 the latter being cut in section on plane denoted by dotted line 5—5 of Fig. 8, the bolt being removed.

Fig. 6 is a view in cross section through a 50 portion of the door and frame with my improved lock secured thereto, the latter being broken away on plane denoted by dotted line 6—6 of Fig. 5.

Fig. 7 is a view of the lock case with the back plate removed.

Fig. 8 is a view in section through the 55 lock case and plate on plane denoted by dotted line 8—8 of Fig. 4, and the parts, however, being reversed end for end, the tumblers being omitted.

Fig. 9 is a view similar to Fig. 8 but on 60 plane denoted by dotted line 9—9 of Fig. 5, and the parts outside of the lock case being omitted.

Figs. 10 and 11 are views of the keys, 65 the former the master key and the latter the ordinary key used in our improved lock.

Our improved locking means, while not confined to any particular use, is especially applicable in securing the doors and lockers 70 such as are provided in gymnasiums and similar places. The articles used by the members and permanently stored in such places commonly occupy much less space than is required by the members for the temporary storage of wearing apparel and 75 other articles during the use by such members of the gymnasium or similar places, which use is generally for comparatively short periods. Comparatively few members 80 occupy a gymnasium or similar place at any one time and it is therefore customary to provide only such numbers of large lockers as may be required for use of a maximum number of such members at any one time, and small lockers to contain the personal 85 equipment of each member for permanent storage the number of the large being much less than those of the small lockers, and space being thus economized.

Our improved lock forming the subject 90 matter of this application is constructed for use in securing the doors both of the small and large lockers hereinabove referred to, the lock being also so made that it will be of little use in other places, and therefore 95 there will be no object to the appropriation of the lock for other uses, and the liability to theft is thereby removed. In the drawings the numeral 10 indicates a door frame and 11 the door of a small locker hereinbefore referred to and commonly used in gymnasiums and similar places, and the numerals 12 and 13 indicate respectively the door frame and door of one of the larger lockers above referred to. These are usually of sheet metal and in order to prevent disengagement of the lock bolt from its keeper by springing the door and frame 100 105

apart we so construct our improved lock that it rigidly secures such door and frame together and prevents their separation while the lock parts are engaged. In accomplishing this result we provide a lock plate 14, preferably dish-shaped, having a bent flange 15 extending from one edge thereof and adapted to pass through a slot 16 through the door frame 10, it being understood and intended that the description herewith applies generally to the doors and frames of both the small and large lockers. This bent flange has a nose 17 adapted to underlie the door frame, and by reason of this structure the door of the locker may be opened without removing the lock from the frame, the latter being swung on the bent flange as a pivot to a position to permit the door to be opened and as shown in Fig. 4 of the drawings, the nose 17 preventing disengagement of the lock plate from the door frame. It will be understood that the nose, flange, and slot are so constructed that by tipping the lock plate when inserting the flange 15 through the slot, the nose may be passed through the slot and in position to engage the back of the frame as shown in Figs. 1 and 4 of the drawings.

A lock case 18 secured to the back face 30 of the lock plate and within the edges of the dish-shaped structure is provided with outwarded flanges 19 to receive screws or other devices for securing the lock case to the lock plate. Openings 20 are formed through the doors 11 and 13, the same numbers being employed in connection with the doors and frames of the large and small lockers as they are the same except for size. These openings are of the shape and size, approximately that of the lock case 18, so that the latter may be readily passed through the openings, as shown in Fig. 6 of the drawings, in which position the lock will be held by means of its bolt 21 which, when thrown, 45 passes behind the door, as shown in the figure of the drawings last referred to. It will be seen that when the lock plate is thus secured to the door with the flange 15 engaging behind the door frame and the plate 50 extending across the gap or crack between the edges of the frame and door, the latter will be so rigidly secured together that it will be impossible to spring them apart sufficiently to permit removal of the lock plate.

55 The case 18 contains a slotted barrel 22 adapted to receive keys, and at one side of the barrel a number of tumblers 23 are pivotally mounted and have slots to receive a lug 24 projecting from the side of the bolt 21, 60 the latter having a tail 25 with a notch to be engaged by a projection from the edge of the key and by means of which the bolt is moved. The barrel, bolt and tumblers just described may be of any well known con-

struction and a further and detailed description is, therefore, omitted herein.

We provide our improved lock with means for indicating to an attendant the fact that a locker has been occupied and therefore needs attention for the cleansing of garments that may have been replaced in the locker or for other purpose. This mechanism consists of a signal plate 26 pivotally attached to the inner surface of the lock plate 14 and adapted to swing across the signal opening 27 through said plate. This signal plate may be designed to denote use of a locker when in either of its positions, in the arrangement herein shown the uncovering of the opening 27, as shown in Figs. 2 and 4, indicating such use of the locker and, therefore, the requirement for attention. In such an arrangement it is preferred that the color of the signal plate be substantially that of the face of the lock plate, and the door immediately back of or in line with the opening 27 may be of any contrasting color to clearly bring out the fact that the opening is uncovered. A spring 28 is so attached to the plate 26 as to force the latter normally to non-indicating position, that is, a position covering the opening 27. A signal actuating bar 29 is pivotally attached to one end of the signal plate, the opposite end of said bar extending through an opening in the lock case 18 within which said bar has a locking notch 30, a bar actuating shoulder 31 and a slot 32 within which the end of a post 33 projecting from a wall of the case is received. The bar actuating shoulder 31 is engaged by a signal actuator 34 slidably mounted against one of the side walls of the lock case, and adapted to be forced in one direction by means of an actuator spring 35. The spring 35 is stronger than the signal plate spring 28 and has, therefore, sufficient force to move the signal plate 26 and uncover the opening 27. A stud 36 projects from the side of the actuator 34 through a slot 37 diagonally arranged in a wall of the case 18, said stud projecting far enough to engage the outer face of the locker door when the lock plate is forced to place, and as shown in Fig. 6 of the drawings. In this operation of forcing the lock plate to place against the outer surface of the door, the stud 36 moving along the slot 37 draws the signal actuator 34 away from the shoulder 31 on the signal actuator bar, and as shown in Fig. 5 of the drawings. The bar 29 is at this time free to be moved by the signal plate 26 under force of its spring 28 and into position to close the opening 27, in which position it indicates that no attention to the locker is required.

A signal controller 38 is pivotally mounted on the post 33 and it has a locking

lug 39 arranged to engage the locking notch 30 in the signal actuating bar 29. A controller lug 40 also projects from the controller into position to be engaged by a controller actuating prong 41 extending from the master tumbler 42, which tumbler is mounted upon the pin supporting the other tumblers of the lock hereinbefore referred to. This master tumbler, except for the 10 prong above mentioned, is of the usual construction and operates in a manner common to many locks in use at the present time.

It being remarked that the lock parts of themselves and independently of our improvement are of ordinary construction in which the master tumbler is operated only by the master key 44 and it being assumed that the parts of the device are in the position in which they have been left when 20 secured to a door by use of said master key, as by an attendant, and as shown in Fig. 1 of the drawings, the operation of the device is as follows:

The operation of the regular occupant's 25 key 43 will not affect the signal apparatus in any manner whatsoever. Therefore, when the occupant throws the bolt 21 by the use of his key to release said bolt from engagement with the door 11 of the small locker (or that 30 of the larger locker) the signal mechanism will not be affected. The lock plate will, however, as soon as the bolt is drawn inward into the case and thus released from engagement with the back surface of the door, spring 35 outwardly at that edge opposite the flange 15, owing to the pressure of the stud 36 against the outer surface of the door and caused by the actuator spring 35. As the signal actuator 34 is thus drawn back by the 40 spring 35 pressure of the actuator against the shoulder 31 will be exerted upon the signal actuating bar 29 and the signal plate 26 will be moved to its indicating position as shown in Figs. 2 and 4 of the drawings. 45 When the locking notch 30 in said bar reaches a position opposite the locking lug 39, the latter will drop into said notch under the action of gravity and the controller actuating spring 45 (either or both) and the 50 signal plate will thus be held in its indicating position until the controller is again moved, as by the operation of the master tumbler 42. The occupant may remove from the small locker such articles as he wishes 55 to use and selecting one of the larger lockers he places his wearing apparel therein, removing the lock plate 14 from the door of the smaller locker to the door 13 of the larger locker and the latter may be secured 60 by the use of his key. When the occupant wishes to again resume his wearing apparel the larger door 13 is unlocked as before described with respect to the small door, the equipment is replaced in the small locker 65 and the lock is removed to the door of the

small locker where it is again secured, and during all of this operation the signal device remains in the position assumed by it when the lock was removed from the door of the small locker, and indicates that the small 70 locker has been used and the consequent requirement for attention by the attendant.

When the attendant withdraws the bolt from behind the door of the small locker and with the master key 44, the operation 75 of the master tumbler 42 by said key will swing the signal controller 38 in position to remove the lug 39 from the locking notch 30 in the bar 29 and the spring 28 will promptly move the signal plate 26 into position 80 to cover the opening 27 and as shown in Fig. 5 of the drawings. When, however, the bolt has been withdrawn, the lock plate 14 will be pressed outwardly by the stud 36 as hereinbefore described, and the operation 85 of the actuator 34, and the bar 29 will move the signal plate 26 to uncover the opening in which position it will be held by the automatic engagement of the locking lug 39 with the notch 30. The lock plate may now be 90 moved to the position shown in Fig. 4, the nose 17 retaining it from disengagement from the frame 10. The door of the locker having been opened and the locker given the required attention and the door being again 95 closed and the lock plate swung to its closed position the master key will be employed to lock the parts. In this operation the master tumbler 42 will again operate to release the lug 39 from the notch 30, and the actuator 100 34 being in a position away from the shoulder 31 the spring 28 will move the signal plate 26 into position to close the opening 27 and as shown in Fig. 1 of the drawings, after which the operation above described 105 may be repeated.

To facilitate the movement of the signal controller 38 a bearing lug 46 projects from one face of the controller and rests against an inner face of the key case. 110

While we have shown and described herein a satisfactory construction of lock embodying our ideas, this may be departed from to a greater or lesser degree and yet be within the spirit and intent of the invention. 115

We claim:

1. A lock structure including means for removably attaching it to a support, lock mechanism including a key operated bolt and another movable member, signal mechanism operatively connected with the lock mechanism, means for operating said movable member of the lock mechanism and the signal mechanism and means controlled by movement of the lock with respect to the 120 door for operating said signal.

2. A lock structure comprising means for removably attaching it to a support and including lock mechanism including a key operated bolt and another movable member, 130

signal mechanism operatively connected with said movable member of the lock mechanism, means operable by the movement of the lock for operating the signal mechanism and means for operating the lock mechanism.

3. A lock-plate, a lock-case secured to the plate and containing lock mechanism including a key operated bolt and another movable member, means including said bolt for securing the plate in place, a signal mechanism operatively connected with said movable member, and means operable by movement of the lock-plate to operate the signal mechanism.

4. A pair of doors, a lock-plate constructed for removable attachment to both of said doors, a lock mechanism mounted on said plate and including a key operated bolt and another movable member, the former to secure the lock plate to said doors, and a signal mechanism operatively connected with said movable member and including an actuating member operable by the movement of the lock-plate.

5. A pair of doors with their frames all of which have openings, a lock-plate having members to fit said openings and including a lock-case formed to pass through one of said openings, lock mechanism within said case and including a key operated bolt to secure the lock-plate in place and another movable member, and a signal mechanism operatively connected with said movable member and including an actuating member operable by the movement of the lock-plate.

6. A lock having mechanism to be operated by a plural number of keys of different construction, means for removably securing the lock in place, and a signal mechanism arranged to be operated by movement of said lock, and also to be key operated by one of said keys only.

7. A lock arranged for operation by a plural number of keys, lock mechanism including a key operated bolt and another movable member, including a master-key, and a signal mechanism arranged to be key-operated by the master-key only, and an operative connection between said signal mechanism and said movable member, arranged to be operated by movement of the lock with respect to the door.

8. A lock including lock mechanism including a key operated bolt and another movable member, a signal device, a signal actuating mechanism including an actuating member arranged to be key-operated by a master-key only, and an operative connection between said signal mechanism and said movable member, arranged to be operated by movement of the lock with respect to the door.

9. A lock constructed for removable at-

tachment to a support, means for securing the lock to the support, lock mechanism including a key operated bolt and another movable member, a signal device, a signal actuating member positioned for contact with and operation by the support in positioning the lock therein, and an operative connection between said signal actuating mechanism and said movable member of the lock mechanism.

10. A lock constructed for removable attachment to a support, means for securing the lock to the support, lock mechanism including a key operated bolt and another movable member, a signal device, a signal actuating member movable in one direction by contact with said support, means for moving said device in the opposite direction, and an operative connection between said signal device and said movable member of the lock mechanism.

11. A lock constructed for removable attachment to a support, means for securing the lock to the support, lock mechanism including a key operated bolt and another movable member, a signal device, key actuated mechanism for operating said device, a signal actuating member adapted to engage said support and to be moved thereby in placing the lock in position and an operative connection between said signal actuating member and said movable member of the lock mechanism.

12. A lock constructed for removable attachment to a support, means for securing the lock to the support and including lock mechanism comprising a key operated bolt and another movable member, a signal device, a connection between said device and said movable member, lock mechanism including a member arranged to be key-operated by the master-key only, and a signal actuator adapted to be operated by reason of contact to said support.

13. A lock constructed for removable attachment to a support, lock mechanism for securing the lock to said support and including a key operated bolt and another movable member, a signal device, a controller connected with the signal mechanism and said signal device, an operative connection between said movable member and said controller, means for operating the controller and means controlled by movement of the lock with respect to the door for operating said signal.

14. A lock constructed for removable attachment to a support, lock mechanism to secure the lock to said support and including a key operated bolt and another movable member, a signal device, means for moving said device in different directions, a controller connected with said movable member and with said device to lock it against move-

ment and to permit its movement and means controlled by movement of the lock with respect to the door for operating said signal.

15. A lock constructed for removable attachment to a support, lock mechanism to secure said lock to the support and including a key operated bolt and another movable member, a signal device, a controller to control the operation of said device, an actuator operatively connected with said movable member and also connected to operate said signal device and means controlled by movement of the lock with respect to the door for operating said signal.

15 16. A lock constructed for removable attachment to a support, lock mechanism for securing the lock to said support and including a special-tumbler comprising an active part of the lock mechanism, a signal device, connections between said special-tumbler and said device for operating the latter and means controlled by movement of the lock with respect to the door for operating said signal.

25 17. A lock constructed for removable attachment to a support, lock mechanism for securing the lock to the support and including a special-tumbler comprising an active part of the lock mechanism, a signal device, a controller connected with said special-tumbler and with said device to control the movement of the latter, means other than said tumbler for actuating said device and means controlled by movement of the lock with respect to the door for operating said signal.

18. A lock constructed for removable attachment to a support, lock mechanism for securing said lock to the support, and including a special-tumbler comprising an active part of the lock mechanism, a signal device, a controller actuated by said special-tumbler and connected with said device, and a signal actuator mounted for movement by contact 45 with the support to which the lock is secured.

19. A lock arranged to be removably placed in position in a door, a lock mechanism and a signal mechanism comprised in said lock and including a member movably 50 mounted to secure the lock in position on the door, an operative connection between the lock mechanism and signal mechanism and means controlled by the movement of the lock with respect to the door for operating 55 said signal.

20. A lock including a lock plate, lock mechanism mounted upon said plate, signal mechanism mounted upon said plate, an operative connection between the lock mechanism and the signal mechanism, means to operate the lock mechanism and a member 60 thereof to removably secure the plate in position on a door and means controlled by the movement of the lock with respect to the door for operating said signal.

21. A lock structure including means for removably attaching it to a support, lock mechanism including a key operated bolt and another movable member, signal mechanism operatively connected with said movable 70 member of the lock mechanism, means for operating the lock mechanism and the signal mechanism, a controller connected with the signal mechanism and held in one position when the lock is in place on a door, and 75 means for moving the controller to another position.

22. A lock having means for removably attaching it to a support, and indicating mechanism comprised in said lock, said mechanism having an arrangement to effect its 80 operation when the lock is removed from said support.

23. A lock having means for movably attaching it to a support, and signal mechanism 85 comprised in said lock and having an arrangement to effect its operation when the lock is moved relatively to its support.

24. A lock arranged to be placed in position on a support, and signal mechanism arranged in said lock and including a signal member and a member operatively connected therewith and movably mounted in position to make contact with the support and also disconnected from other members of said 95 mechanism for movement independently thereof.

25. A lock having means for removably attaching it to a support, and an arrangement of mechanism comprised in said lock 100 and including a movably mounted member and an indicating member operatively connected therewith and arranged to be operated when the lock is moved with respect to said support, and means to effect operation 105 of said movably mounted member by means of a key.

26. A lock comprising a movably mounted indicating member arranged to be placed in a set and unset condition, means for placing 110 said member in one of said conditions by movement of the lock with respect to a support, and key operated mechanism for changing said set condition.

27. A lock comprising two sets of mechanisms, a signal mechanism and a lock mechanism, means for movably attaching said lock to a support, means operatively connected with one of said mechanisms for setting it by movement of the lock with respect to 115 the support, and key operated means for effecting movement of said mechanism from its set position.

28. A lock comprising a plurality of sets of mechanisms, one of said mechanisms being an indicating mechanism arranged to be placed in a set and unset condition and including a member for placing it in one of said conditions by a movement of the lock 125 with respect to a support, a key operated 130

member for changing said set condition, and key operated means for operating the other of said mechanisms.

29. A lock comprising a plurality of sets of mechanisms, one of said mechanisms being an indicating mechanism arranged to be placed in set and unset conditions, means for placing said mechanism in one of said conditions by movement of the lock with respect to said support, means for changing said condition, and key operated means for actuating the other of said mechanisms while unaffected the mechanism arranged to be placed in set and unset conditions.

10 15 30. A lock having means for removable attachment to a support and comprising a lock mechanism and an indicating mechanism, a key to operate the lock mechanism while unaffected said indicating mechanism, and means for operating said indicating mechanism.

20 31. A lock having means for removable attachment to a support and comprising a

lock mechanism and an indicating mechanism, and means for placing said indicating mechanism in one condition by movement of the lock with respect to said support and operable by a key only when in said condition.

32. A portable lock comprising a lock plate, lock mechanism on said plate, indicating mechanism on said plate, and means operatively connected with the indicating mechanism and also operating to detachably secure said plate to a support, whereby the plate is removably detached at each operation of the lock mechanism.

33. A lock comprising a plurality of sets of mechanisms, one of said mechanisms being an indicating mechanism arranged to be placed in set and unset conditions, means for placing said mechanism in one of said conditions, and key operated means for operating it only when in said last mentioned condition.

ELMER B. STONE,
CHARLES E. JOHNSON.
